(57) **CLAIM**

The ornamental design for a golf accessory belt, as shown and described.

DESCRIPTION

FIG. 1 is a perspective view of the golf accessory belt; FIG. 2 is a front elevational view of the golf accessory belt; FIG. 3 is a back elevational view of the golf accessory belt; FIG. 4 is a top plan view of the golf accessory belt; FIG. 5 is a bottom plan view of the golf accessory belt; FIG. 6 is a right side elevational view of the golf accessory belt; FIG. 7 is a left side elevational view of the golf accessory belt; FIG. 8 is a front elevational view of the golf accessory belt; and, FIG. 9 is a front elevational view of the golf accessory belt. The broken lines define the bounds of the claimed design and form no part thereof. The golf tees, the divot repair tool, and the towel are shown for environmental purposes only and form no part of the claimed design. The broken lines symbolize breaks in the length of the article in which the claimed design is embodied. The appearance of any portion of the article between the broken lines forms no part of the claimed design.
